CLAIM

The ornamental design for an informational terminal unit, as shown and described.

DESCRIPTION

FIG. 1 is a perspective view of an informational terminal unit, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is an enlarged fragmentary view of the portion thereof surrounded by box 8 in FIG. 1.

1 Claim, 6 Drawing Sheets
